United States Patent Office.

WILLIAM F. MORTON, OF NEW HAVEN, CONNECTICUT.

Letters Patent No. 74,117, dated February 4, 1868.

IMPROVEMENT IN CARRIAGE-WHEELS.

The Schedule referred to in these Letters Patent and making part of the same.

TO ALL WHOM IT MAY CONCERN:

Be it known that I, WILLIAM F. MORTON, of the city and county of New Haven, in the State of Connecticut, have invented a new and useful Improvement in Carriage-Wheels, as an improvement on my patent dated May 28, 1867; and I do hereby declare that the following is a full, clear, and exact description of the construction, character, and operation of the same, reference being had to the accompanying drawings, which make part of this specification, in which—

Figure 1 is a perspective view of the double band or collar, with the connecting-bars which hold the two parts together, as ready for use.

Figures 2, 3, and 4 are cross-sections of the double band or collar, when the outside surface is made of different shapes.

My improvement on my former patent consists in making the band or collar of less dimensions in its outer diameter, and of different shape in the cross-section, and designed to have but two spokes inserted between each two of the bars; and the annular disk or web being narrower, it does not extend so far on to the spokes, thus presenting a smaller circle, so that I can use fewer spokes, and yet form the apparently solid mass of wood at the outer verge of the double collar, whereby I can make a stronger, as well as a cheaper, lighter, and neater wheel than in the other way.

I make the double band or collar, A A, &c., of malleable cast iron, or any other suitable material, by casting it in one piece with the connecting-bars a a, &c., substantially as shown in fig. 1, (in which particular it is like the patent issued to me, May 28, 1867,) so that I can drive it on to the wooden hub of the wheel to its proper position, and drive in the spokes between the connecting-bars a a, &c., and into the mortises in the hub, so that the double band or collar will equally bind the wooden hub and the inner ends of the spokes, while the inner ends of the spokes, by passing between the bars a a, &c., and their tenons entering the mortises in the wooden hub, will hold the double band or collar A A, &c., firmly in its proper place, and make the whole as one fixed and solid mass, each part binding the other; in this particular it much resembling my former patent, before mentioned.

But in the present case I do not make the double band or collar in the form of two collars to bind the hub, and two flanges to support the spokes, but I make each of the collars of a general mass in its cross-section, that is, a complete right-angled triangle, as represented in fig. 4, or by leaving a small bead or projection at each acute angle, as represented in fig. 2, or with a curved instead of a right-lined hypotenuse, as represented at a, fig. 3, having one of the sides or legs which contains the right angle, as b, press upon the hub, as indicated in fig. 1, and the other leg, as c, sustain the spokes, while the side d, which subtends the right angle, may be like fig. 2, 3, or 4, or it may be cast or turned in any other suitable form of ornamental surface, but retaining the strength.

By casting the article in either of these forms in the cross-section, gives it much greater strength, so that it is not necessary to make the vertical surface e to sustain the spokes, and consequently the connecting-bars, near so wide, so that it will not extend near so far upon the spokes, and for that reason the outer point of the junction of the spokes may be nearer the wooden hub, and therefore in a smaller circle, so that fourteen spokes may serve instead of eighteen, thus saving four spokes in a wheel, or sixteen in a set, so that I not only use less iron for the double collar, but also less spokes, and thereby leaving the wooden hub much stronger, while the spokes will be better supported, as I use seven connecting-bars, and only place two spokes between each two bars. In this form I can make a cheaper, stronger, and lighter wheel, with a neater finish.

I cast the connecting-bars a a, &c., fig. 1, of a triangular or wedge-shape in the cross-section, with the point of the wedge, or least angle of the triangle, outward, so that the spokes will pass in more readily, and yet join each other at the outer verge of the collar, so as to form, in appearance, one mass of wood at that circle.

I find that when I make the double collar in the form above described, the vertical side, C, which supports the spokes, need only be from three to five-tenths of an inch in elevation for wheels for light carriages.

Having made the double collar A A, &c., with the connecting-bars a a, &c., and mortised the wooden hub, as before described, I drive the double collar on to the hub to the proper position, and drive in two spokes

between each two of the connecting-bars α α , &c., when that part of the wheel will be complete, and ready to receive the felloes.

For a very large wheel, it may be advisable to use eight bars and sixteen spokes, and for very small wheels, six bars and twelve spokes may be sufficient; but for common-sized wheels I recommend seven connecting-bars and fourteen spokes, so shaped and fitted that nothing will be seen above the verge of the double collar but the mass of wood formed by the junction of the spokes, when the wheel is finished and fitted for use.

What I claim as my invention, and desire to secure by Letters Patent, is—

The hub, cast in one piece with the collars A A and connecting-bars α α , when constructed in the shape and proportions as described.

WM. F. MORTON.
